(57) **CLAIM**

The ornamental design for computer equipment, as shown and described.

DESCRIPTION

FIG. 1 is a front perspective view from above and the left side of the computer equipment showing our design; FIG. 2 is a rear perspective view from above and the left side thereof;

FIG. 3 is a top view thereof;

FIG. 4 is bottom view thereof;

FIG. 5 is a front view thereof;

FIG. 6 is a rear view thereof;

FIG. 7 is a right side view thereof; and,

FIG. 8 is a left side view thereof.

The broken lines throughout the drawing figures are included for the purpose of illustrating portions of the equipment that form no part of the claimed design.
